UNITED STATES PATENT OFFICE.

GEORGE EDWARD FIGG, OF MONTREAL, CANADA.

DESIGN FOR A TIE-SHIELD.

SPECIFICATION forming part of Design No. 35,337, dated November 26, 1901.

Application filed September 27, 1901. Serial No. 76,811. Term of patent 3½ years.

To all whom it may concern:

Be it known that I, GEORGE EDWARD FIGG, a subject of His Majesty the King of Great Britain, residing in the city and district of 5 Montreal, Province of Quebec, Canada, have invented and produced a new and original Design for a Tie-Shield, of which the following is a specification, reference being had to the accompanying drawing, forming part thereof.

10 The figure illustrates the wire shield of my invention in elevation, the view being from the rear.

As shown in the drawing, the leading or material feature of my design consists of a 15 wire having a plurality of twists and curves forming in the center the eyes A and immediately beneath the stud-hole B, which converges at its lower end. The spring twists C are to one side of the center portion and

continue in opposite directions in the elongated portions D, which are curved down toward their outer ends to form the looped portions E, as indicated in the drawing.

It will be noticed that the stud-hole B is designed to fit over the shirt-stud and the 25 loops E to fit inside the collar-bands.

Having described my invention, what I claim as new, and desire to secure by Letters Patent, is—

The design for a tie-shield, as herein shown 30 and described.

Signed at Montreal this 25th day of September, 1901.

GEORGE EDWARD FIGG.
